POTENTIOMETER

Manfred J. Johnson, Naugatuck, Conn.

Application May 9, 1939, Serial No. 272,606

10 Claims. (Cl. 172—239)

This invention relates to potentiometer systems, and, more particularly, to means for controlling the operation of the apparatus.

The problem that has been present in devices of this type is that of controlling the operating motor when a balanced condition exists. It was proposed to obtain this result by short-circuiting the input terminals of the motor or to provide a balanced field which would tend to hold the motor in braked position and control its operation by oppositely wound field coils. In small motors of the fractional horsepower type, however, the regulation is poor, and, therefore, but small braking effect is obtained by short-circuiting the input of the motor.

An object of the present invention is to provide the potentiometer in which the driving means is effectively braked immediately upon the balanced condition being reached or the control circuit for the balancing motor becoming ineffective to drive the motor. This is accomplished by the present invention by applying to the armature shaft of the motor which drives the slide wire contact a strong dynamic brake. This brake can either be in the form of a direct current winding on the pole piece to cooperate with the rotor of the motor, or it can be a separate field reacting on a separate armature carried by the motor shaft.

In the present preferred form of the invention, the brake is normally applied to the motor to hold it against rotation and upon the control means for the motor being rendered operative to rotate the motor in either direction, the brake will be removed, and, upon the circuit becoming balanced and the control means rendered inoperative, the brake will be immediately applied to the motor to stop it with but a small fraction of a revolution.

The brake, according to the present invention, may be controlled in several ways. In the preferred form of the invention the braking field is supplied with D. C. by means of a thermionic tube whose grid is connected to the control circuit in such a manner that, upon the current flowing in the control circuit to cause the motor to run in either direction, the grid becomes biased to stop the flow of direct current to the braking field and thus release the brake. Immediately upon the current ceasing to flow in the control circuit, the grid of the thermionic tube is returned to its normal potential and current again flows in the braking circuit to apply a braking force to the rotor.

The braking of the motor can also be accom-

plished by providing a means in the control circuit for the motor for opening the circuit to the braking field upon the control means for the motor becoming operative. Also, the motor can be provided with a separate direct current field which, when energized, will oppose and neutralize the direct current field—the energization being controlled by the circuit controlling the operation of the motor to cause it to rotate in either direction.

If desired, the braking field can be controlled mechanically so that the braking circuit is opened during that period in which the drum contacts are in position to be engaged by the deflectable contact member of the galvanometer to cause the motor to run in either direction to balance the thermocouple circuit upon off-zero movement of the deflectable member. In this form of the invention, the brake is normally applied to the motor but is periodically removed.

The present invention, in its broader aspects, contemplates the application of a dynamic braking action to the motor of the balancing circuit so that the latter is stopped immediately upon the balance being obtained. It will be seen, therefore, that a very accurate control will result inasmuch as it will avoid overrunning and reduce to a minimum of time the balancing operation.

Other features and advantages will be apparent from the specification when considered in connection with the drawings, in which:

Figure 1 shows a diagrammatic view of one form of the invention in which the brake is controlled through the thermionic tube.

Fig. 2 shows a diagrammatic view of the circuit in the form of the invention in which the direct current field is opened by a relay in accordance with the operation of the motor.

Fig. 3 is a diagrammatic view of the system in which an opposing D. C. field is utilized to counteract the braking field when the motor is energized in either direction.

Fig. 4 is a diagrammatic view of another form of the invention in which the field of the motor is energized with direct current to apply a brake to the rotor and is adapted to be connected to a supply of A. C. when it is desired to operate the motor.

Fig. 5 is a diagrammatic view of another form of the invention wherein the braking field is mechanically controlled.

Fig. 6 shows an end view of the motor, the field and shading coils thereon, the fields being

adapted to be connected to A. C. or D. C. current.

Fig. 7 shows the side view of the motor showing the separate pole piece for the braking field and a rotor on the armature shaft of the motor cooperating therewith.

Fig. 8 is a form of the invention in which the braking field is wound on the same pole piece as the energizing field.

Fig. 9 shows a form of the invention in which the braking field and opposing field are wound on the pole piece with the energizing field.

In the form of the invention shown in Fig. 1, the control system is similar to that shown in my Patent No. 2,109,776, wherein a galvanometer 20 or deflection instrument is provided with a long needle-like contact 21 which is periodically depressed by a bail 22 into engagement with either of a pair of contacts 23, 24 on a rotating drum 25. The drum is made of insulating material, and the contacts taper toward the middle of the drum, leaving a spaced in-between which is engaged by the needle when in zero position. The drum is rotated by a motor 26 connected to the supply lines.

The galvanometer winding 27 is connected to a thermocouple 28 or other source of voltage which is varied according to a change of condition. One side of the thermocouple is connected to the coil 27, while the other side is connected to a movable arm 30 having a contact 31 adapted to engage a slide wire 32 which is mounted on the periphery of a stationary disk 33. The other side of the slide wire is connected to a resistance 34 and a calibrating resistance 35, the latter having a movable contact 36 connected through a switch 37 to a source of current 38, which in turn is connected to the other end of the slide wire and to the galvanometer winding.

When the change in E. M. F. generated by the thermocouple occurs current flows through the galvanometer coil, the needle 21 will be deflected and the increase or decrease in potential is counterbalanced by the adjustment of the slide wire.

The adjustment of the slide wire is accomplished in the illustrated form of the invention by use of a shaded-pole motor 39 having a constantly energized field 40 and oppositely wound shading coils 41, 42 connected to the plates 43, 44 of a pair of thermionic devices or tubes 45, 46 through a transformer 47. The filaments 48, 49 of the tubes 45, 46, are energized from a winding 50 on a transformer 51 and the grids 52, 53 are connected through suitable resistors to be energized from winding 54 of the transformer, and are connected with the contacts 23, 24 on the drum in such a manner that, upon the needle engaging one of the contacts, it will change the potential on either grid 52, 53 and cause the current to flow in the corresponding pair of shading coils to operate the motor in the proper direction to move the slide wire contact to balance the thermocouple circuit.

The constantly energized field 40 of the motor in some instances might be sufficient to brake the motor shaft quickly upon a balance being attained, however, when the motors are made in the nature of fractional horsepower motors the braking action of this field is not reliable.

According to the present invention, a separate braking means is utilized for applying a dynamic brake to the motor to stop it immediately upon

the control circuit for energizing it for rotation in either direction becoming ineffective.

In the form of the invention shown in Fig. 1, a separate pole piece 55 is secured to the frame 5 of the motor and a separate rotor 56 preferably of the squirrel cage type is secured to the shaft of the motor so as to cooperate with the pole piece. A field 57 is wound on the pole piece and when energized with direct current it will, due to the generation of voltage in the rotating rotor, dynamically brake the same and hold it against rotation.

The D. C. current may be supplied to the braking field in many ways. In the forms of the invention illustrated in Fig. 1, a brake controlling thermionic tube 58 has its filament 59 connected across the transformer winding 50 supplying current to the filaments of the control tubes 45, 46 and its plate 60 connected to the 20 D. C. field.

The grid 61 of the tube 58 is connected in the circuit so that it normally has the filament potential impressed thereon which causes a pulsating direct current to be impressed on the field 25 coil from winding 62 of transfer 51. A condenser 63 shunted across the lines smooths out the pulsating current.

The grid is also connected to the plate circuit of the tubes 45, 46 through a drop resistor 64, 30 and a winding 65 on the transformer 51. This connection is normally inoperative to control the grid, however, upon a change of voltage occurring in the thermocouple, the galvanometer needle will swing to right or left and engage 35 either contact 23, 24, changing the potential of the grid 52, 53 in the corresponding control tube 45, 46 to that value in which current will pass to the plate 43, 44 and energize the corresponding shading coils. This flow of current through 40 the drop resistance will change the potential on the grid 61 of the tube controlling the brake and will stop the flow of current between the filament and the plate of this tube, and in effect open the circuit to the direct current field.

This potential will remain on the grid 61 of the brake control tube as long as current passes in the circuit controlling the rotation of the motor.

As soon as the motor has adjusted the slide wire so that a balanced condition exists in the thermocouple circuit and the galvanometer needle moves to zero position in which it no longer engages either contact on the drum, the grids of the control tubes will assume their normal potential and current will cease to flow in the control circuit. Immediately upon the current ceasing to flow in the control circuit, the potential on the grid 61 of the brake control circuit will again assume the filament potential, and braking current will flow to the braking field and quickly stop rotation of the motor.

Thus it will be seen that the braking action is immediately removed from the motor upon its energization to move it in either direction to balance the circuit, which braking action is restored as soon as the thermocouple circuit is balanced, thus effectively preventing any overrunning of the motor.

In the form of the invention shown in Fig. 2, the control for balancing the circuit is the same as described in Fig. 1. In this form of the invention, the braking field 70 may be applied directly to the pole piece of the motor to coact with the rotor thereof, or can be applied as a separate

pole piece and a rotor secured to the motor shaft to cooperate therewith.

The braking field is supplied with D. C. current from the power line through a transformer 71 and a rectifier 72. The braking field circuit has a normally closed switch 73 for completing the circuit so that the brake is normally applied to the motor. To open the circuit to the braking field at the switch, the present invention provides a relay 74 connected in the plate circuits of the control tubes and operable, upon current flow in the said plate circuits to cause the motor to rotate, to release the brake.

Thus it will be seen that, upon a change of voltage being generated in the thermocouple, the needle will deflect to engage either contact on the drum, and will cause current to flow in the corresponding control tube plate circuit to load the shading coils to control the direction rotation of the motor. As soon as current flows in the plate circuit, the relay 74 will operate to open the switch 73 in the braking field circuit and remove the brake from the motor. As soon as the motor has moved the slide wire contact to that point in which the circuit is again balanced, the needle of the galvanometer will be in zero position and will stop the flow of current in the control tube and deenergize the relay 74, whereupon the switch in the braking circuit will again close and apply the brake immediately without any overrunning of the motor.

In the form of the invention shown in Fig. 3, the control for the motor for balancing the circuit is similar to that shown in Fig. 1. In this form of the invention, a braking field 80 is either wound on the pole piece of the motor or on the separate pole piece to cooperate with a separate rotor on the motor shaft. The braking field is supplied with a D. C. current from the power lines through a transformer 81 and a rectifier 82. A variable resistance 83 is included in the circuit so that the amount of braking action can be varied.

The pole piece carrying the braking field has wound thereon, in opposition to the braking field, a second field 84. This opposing field is connected in the plate circuit and is supplied with energy from a transformer winding 85. As soon as the thermocouple generates a voltage to deflect the needle to engage either of the contacts 23, 24, the corresponding control tube is rendered conductive whereupon a current flows in the plate circuit to rotate the motor in the desired direction to balance the circuit. The current flowing in the plate will also flow in the opposing field circuit which will produce a field of such a magnitude as to oppose and neutralize the effect of the braking field, and thus permit the motor to run in the desired direction and adjust the slide wire.

As soon as the thermocouple circuit has been balanced, the needle of the galvanometer will again be brought to zero position, and the control tube rendered nonconductive. This will remove the opposing field and permit the braking field to immediately stop the motor, thus preventing overrunning of the adjusting motor.

In the form of the invention shown in Fig. 4, the control circuit for balancing the thermocouple circuit is substantially the same as shown in Fig. 1. In this form of the invention, a main field winding 40 of the motor is connected to a switch 90. The switch normally connects the field to a source of D. C. current from the power lines, through a transformer 91 and a rectifier 92.

5 The switch is controlled by a relay 94 in the plate circuit of the control tubes and operates to shift the field winding 40 from the source of a D. C. to a source of A. C. when it is desired to balance the circuit.

When current flows in the thermocouple circuit, the galvanometer needle will deflect to engage either contact. This will render the control tube associated with the contact operative to pass current to load the shading coils to rotate the motor in the desired direction. This will quickly operate the relay 94 to pull the switch over and connect the field to the source of A. C. current. The plate circuit of the control tubes, according to this form of the invention, receives its initial energization from a transformer winding 93 and immediately upon the operation of the switch the plate circuit will be also energized by the voltage generated in the shading coils.

10 20 As soon as the circuit is balanced, the galvanometer needle will return to zero position and the control tube again becomes nonconductive. This will immediately deenergize the relay 94, and the switch will again close the circuit to the field through the direct current supply, and brake the motor very quickly to prevent overrunning.

25 30 In the form of the invention shown in Fig. 5, the motor is controlled in a manner similar to that described in connection with Fig. 1. The contacts 23', 24' on the drum in this form of the invention are provided with a straight cut-off line 100, and taper outwardly so that their forward edges 101 extend along the drum as shown. The contact 21 will always open the circuit at the same time, but can start the operation of the motor at different times according to the amount of deflection. The motor is braked by a field 102 which is energized with direct current from the line through a transformer 103 and a rectifier 104. The energizing circuit for the brake includes a pair of normally closed contacts 105, 106, which are mechanically actuated and opened during that period of the revolution of the drum when the contacts are in a position to cooperate with the contact 21 to remove the braking action of the field. This is accomplished by providing a cam 107 which is secured to the shaft of the drum having a cam face which will open the contacts for the duration of this period.

35 40 45 The cam will open the circuit to the braking field just prior to the contacts 23' and 24' moving into the zone in which they may engage the contact 21 so that the motor will be free to rotate in either direction upon the detection of an off-zero movement so as to balance the circuit.

50 55 60 Thus it will be seen that the braking field circuit is not controlled by the control tubes for rotating the balancing motor but is mechanically opened, as by operation of the cam 107, for the period in each revolution of the drum during which the motor might be operated in either direction to balance the thermocouple circuit. It will be clear that once the motor has been braked and stopped, upon the closing of the contacts 105, 106, it is not necessary that the brake be applied continuously as the motor will not tend to rotate after it has once been brought to a stop.

65 70 75 Figs. 6 through 9 show various forms of motors for adjusting the slide wire to balance the thermocouple circuit. While it is to be understood any split phase motor or reversible A. C. motor may be utilized to drive the slide wire contact, the motors used for purpose of illustration are those in which oppositely wound shading coils control the direction of rotation of the motor.

In the motor shown in Fig. 6, the main field coil 40 is of the type which can be connected to either A. C. or D. C. as shown in Fig. 4.

In the form of the invention shown in Fig. 7, the shaded pole motor is provided with a secondary pole piece 55 and a rotor 56 mounted on the armature shaft to cooperate therewith. The secondary pole piece has a field coil 57 which is adapted to be connected to the direct current source to hold the motor against rotation and have its circuit opened to permit the motor to be driven in either direction.

Fig. 8 shows the form of the invention in which the A. C. field winding 40 and D. C. field winding 70 are wound on the same pole piece. This type of motor, for example, can be used with the forms of the invention shown in Fig. 2.

Fig. 9 shows the normal A. C. field winding 40, and the two opposing D. C. field windings 80, 84 wound on the same pole piece. This type of motor can be used on the form of the invention shown in Fig. 3.

Variations and modifications may be made within the scope of this invention and portions of the improvements may be used without others.

I claim:

1. In a potentiometer system, a slide wire; means for unbalancing said system in accordance with a change in condition; a galvanometer controlled by said means and connected in circuit with the slide wire; means including an alternating current motor having a continuously energized A. C. field, two wire-wound shading coils and a D. C. field and including thermionic devices having their plate circuits energized by said shading coils and controlled by said galvanometer for adjusting the slide wire in accordance with the direction of off-zero movement of the galvanometer; means for energizing the D. C. field to hold the rotor of the motor against rotation; and means for deenergizing the D. C. field when the thermionic devices are operative to actuate the motor to adjust the slide wire.

2. In a potentiometer system, a slide wire; means for unbalancing said system in accordance with a change in condition; a galvanometer controlled by said means and connected in circuit with the slide wire; means including an alternating current motor having a rotor, a continuously energized A. C. field and two sets of wire-wound shading coils and including thermionic devices having their plate circuits energized by the shading coils and controlled by the galvanometer for adjusting the slide wire directionally in accordance with off-zero movements of the galvanometer and quantitatively in accordance with the extent of said off-zero movements; and a direct current braking field normally operative to hold the rotor against rotation and released when the thermionic devices are rendered conductive to load the shading coils to control the operation of the motor to balance the circuit.

3. In a potentiometer system, a slide wire; means for unbalancing said system in accordance with a change in condition; a galvanometer controlled by said means and connected in circuit with the slide wire; means including an alternating current motor having a rotor, a continuously energized A. C. field and two sets of wire-wound shading coils and including thermionic devices having their plate circuits energized by the shading coils and controlled by the galvanometer for adjusting the slide wire directionally in accordance with off-zero movements of the galvanometer and quantitatively in accordance with the extent of said off-zero movements; and a direct current braking field normally operative to hold the rotor against rotation and released when the thermionic devices are rendered conductive to load the shading coils to control the operation of the motor to balance the circuit.

4. In a potentiometer system, a slide wire; means for unbalancing said system in accordance with a change in condition; a galvanometer controlled by said means and connected in circuit with the slide wire; means including an alternating current motor having a continuously energized A. C. field and two sets of wire-wound shading coils and including thermionic devices having their plate circuits energized by the shading coils and controlled by the galvanometer for adjusting the slide wire directionally in accordance with off-zero movements of the galvanometer and quantitatively in accordance with the extent of said off-zero movements; a circuit including direct current braking field normally operative to hold the rotor against rotation, said relay being rendered inoperative to supply the current to the braking field upon operation of the thermionic devices to load the shading coils to control the operation of the motor to balance the circuit.

5. In a potentiometer system, a slide wire; means for unbalancing said system in accordance with a change in condition; a galvanometer controlled by said means and connected in circuit with the slide wire; means including an alternating current motor having a continuously energized A. C. field and two sets of wire-wound shading coils and including thermionic devices having their plate circuits energized by the shading coils and controlled by the galvanometer for adjusting the slide wire directionally in accordance with off-zero movements of the galvanometer and quantitatively in accordance with the extent of said off-zero movements; a circuit including direct current braking field normally operative to hold the rotor against rotation; and a relay operable to alter the braking circuit upon operation of the thermionic devices to load the shading coils to control the operation of the motor to balance the circuit.

6. In a potentiometer system, an adjustable slide wire; means for unbalancing said system upon a change in condition; means for adjusting the slide wire to rebalance the system including a reversible motor; means for controlling the direction and extent of rotation of the motor in accordance with the variations and the magnitude of the condition; a braking field normally applying a braking force to the rotor of the motor; and means for producing an opposing field for counterbalancing the braking field and rendering it inoperative upon the control means being rendered operative to cause the motor to rotate in either direction.

7. In a potentiometer system, a slide wire; means for unbalancing said system in accordance with a change in condition; a galvanometer controlled by said means and connected in circuit with the slide wire; means including an alternating current motor having a continuously energized A. C. field and two sets of wire-wound shading coils and including thermionic devices having their plate circuits energized by the shading coils and controlled by the galvanometer for adjusting the slide wire directionally in accordance with off-zero movements of the galvanometer and quantitatively in accordance with the extent of said off-zero movements; a direct current braking field normally operative to hold the rotor against rotation; and a second direct current field rendered operative to counterbalance said braking field upon operation of the thermionic devices to load the shading coils to control the operation of the motor to balance the circuit.

8. In a potentiometer system, a slide wire; means for unbalancing said system in accordance with a change in condition; a galvanometer controlled by said means and connected in circuit with the slide wire; means including an alternating current motor having a continuously energized A. C. field, two wire-wound shading coils and two oppositely wound D. C. fields, and thermionic devices having their plate circuits energized by said shading coils and controlled by said galvanometer for adjusting the slide wire in accordance with the direction of off-zero movement.

of the galvanometer; means for continuously energizing one of the D. C. fields to electrically lock the rotor against rotation; and means for energizing the other D. C. field to oppose and counterbalance the first D. C. field upon the thermionic devices being rendered operative to load the shading coils to adjust the slide wire to balance the system.

8. In a potentiometer system, an adjustable slide wire; means for unbalancing said system upon a change in condition; means for adjusting the slide wire to rebalance the system including a reversible motor having a braking field thereon; means for controlling the direction and extent of rotation of the motor in accordance with a variation and magnitude of the condition; means for normally applying direct current to the braking field to dynamically brake the motor and hold it against rotation; and means for cutting off the supply of direct current to the braking field when the control means is in operative relation to rotate the motor in either direction.

9. In a potentiometer system, an adjustable slide wire; means for unbalancing said system upon a change in condition; means for adjusting the slide wire to rebalance the system including a reversible motor having a braking field thereon; means for controlling the direction and extent of rotation of the motor in accordance with

a variation and magnitude of the condition; means for normally applying direct current to the braking field to dynamically brake the motor and hold it against rotation; and mechanically 5 operated means for opening the circuit to the braking field when the means for controlling the direction and extent of rotation of the motor is in position to be effective to control said motor.

10. In a potentiometer system, a slide wire; 10 means for unbalancing said system upon a change in condition; an adjusting motor connected to said slide wire to move it to balance said system; a galvanometer to rebalance the system connected in the circuit of the slide wire 15 and having a deflectable member; a rotatable drum having contacts thereon to cooperate with the deflectable member to control the direction and extent of rotation of the adjusting motor in accordance with the variation and magnitude of the condition; a braking field for the motor; means for normally applying a direct current to the braking field to hold the motor against rotation; and means operating in timed relation with the drum for opening the circuit to the braking field during the period when the contacts on the drum are in position to cooperate with the deflectable member to cause the motor to rotate in either direction.

MANFRED J. JOHNSON,
